CLAIM

The ornamental design is for a docking station for rugged laptop computer, as shown and described.

DESCRIPTION

FIG. 1 is a top, front and right side perspective view showing a first embodiment of my new design;

FIG. 2 is a top, rear and left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a reference perspective view of a rugged laptop computer installed on my new design;

FIG. 10 is a top, front and right side perspective view showing a second embodiment of my new design, the only difference being the absence of the lock, it being understood that all other surfaces are the same as those of the first embodiment;

FIG. 11 is a top, rear and left side perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof; and,

FIG. 18 is a reference perspective view of a rugged laptop computer installed on my new design.

The broken lines are directed to environment and are for illustrative purposes only. The broken lines form no part of the claimed design.
